(57) **CLAIM**

The ornamental design for a cigarette lighter, as shown and described.

DESCRIPTION

FIG. 1 is a perspective view of a cigarette lighter showing my new design;

FIG. 2 is a front elevational view thereof;

FIG. 3 is a rear elevational view side thereof;

FIG. 4 is a left end elevational view thereof;

FIG. 5 is a right end elevational view thereof;

FIG. 6 is a top plan view thereof;

FIG. 7 is a bottom plan view thereof;

FIG. 8 is a perspective view showing the cover in open position; and,

FIG. 9 is a fragmentary perspective view showing the bottom of the lighter in its open position.

The claimed design is fragmentarily shown for convenience of illustration.
